Pls. 299

E. S. Archer and
R. F. Warner of Philadelphia Pa.
Letters Patent. No. 299- Dated July 9, 1850.

The Schedule referred to in these Letters Patent & making part of the same.

To all whom it may concern:

Be it known that we Ellis S. Archer and Redwood F. Warner of the City of Philadelphia in the State of Pennsylvania have produced and invented new patterns for a Lamp, and as no written description can convey an idea of the style and patterns, we refer to the annexed drawing of the same.

We claim the ornamental design of the column or pedestal, the oil cup and the border round the globe Holder set forth in the accompanying drawing as our original design -

Witnesses.
